UNITED STATES PATENT OFFICE.

FRANCIS C. KOENIG, OF PHILADELPHIA, PENNSYLVANIA, ASSIGNOR TO
REINHOLD G. LEDIG, OF SAME PLACE.

DESIGN FOR A LAMP-BASE.

SPECIFICATION forming part of **Design No. 22,444**, dated **May 16, 1893**.

Application filed April 18, 1893. Serial No. 470,895. Term of patent $3\frac{1}{2}$ years.

To all whom it may concern:

Be it known that I, FRANCIS C. KOENIG, a subject of the Emperor of Germany, (having resided one year last past in the United States, 5 and declared my intention of becoming a citizen thereof,) residing in the city and county of Philadelphia, State of Pennsylvania, have invented and produced a new and original Design for the Base of a Lamp, of which the 10 following is a specification, reference being had to the accompanying drawing, forming part thereof.

The leading feature of my design for the 15 base of a lamp, is the scroll configuration of the same.

In the drawing: A designates the top of the base of a lamp, B the central portion, and C the bottom part or legs. The top A is formed of scrolls D, which are superimposed on the scrolls E of the central portion. The bottom part C is formed of scrolls F, which extend from the scrolls E to the corners of the base, and are joined by the scrolls F.

What I claim is—

The design for the base of a lamp, substantially as shown and described.

FRANCIS C. KOENIG.

Witnesses:

JOHN A. WIEDERSHEIM,
A. P. JENNINGS.
